ELECTRICAL CONTROL FOR WATER
DISTRIBUTORS

Leonard O. Keefer, Spokane, Wash.

Application March 25, 1946, Serial No. 656,800

2 Claims. (Cl. 200—38)

1

This invention relates to an electrically operated sprinkler valve system and it is one object of the invention to provide a valve system so controlled that the length of time a valve will be open for discharge of water may be accurately controlled and also a valve also opened and closed at a predetermined time of day or night.

Another object of the invention is to provide a sprinkler valve system wherein the power unit consists of clock works adapted to be so set that after the clock works have been set in operation opening and closing of valves will be automatic and in predetermined timed relation to each other.

Another object of the invention is to provide a sprinkler valve system wherein the circuit for a motor includes switches adapted to be simultaneously moved and one opened while the other is closed, there being also provided a switch operated by relay in series with the alternately opening and closing switches.

Another object of the invention is to provide a sprinkler valve system which is efficient in operation and not liable to get out of order.

The invention is illustrated in the accompanying drawings wherein:

Fig. 1 is a perspective view of the device.

Fig. 2 is a sectional view taken vertically through the device along the line 2—2 of Figure 4.

Fig. 3 is a wiring diagram.

Fig. 4 is a fragmentary view showing mechanism in the casing in side elevation.

Fig. 5 is a fragmentary sectional view taken along line 5—5 of Figure 4.

This improved time controlled device is particularly adapted for use in connection with a sprinkler system of the type shown in my co-pending application filed March 1, 1946, Ser. No. 651,251, wherein valves are successively opened and closed by mechanism driven by an electric motor from which rotary motion is intermittently transmitted to a shaft carrying cams for effecting opening and closing of the valves, the motor having a circuit in which are disposed mercury switches mounted at ends of a rocker bar pivoted midway its length and tilted to alternately open and close the mercury switches. Such a motor is shown in Figure 3 of the accompanying drawings and indicated by the numeral 1.

2

and in this figure there has also been shown mercury switches 2 and 3 corresponding to the switches mentioned above and mounted at opposite ends of a rocker bar 4 pivotally mounted midway its length as shown at 5. In the present showing the switch 2 is closed and switch 3 is open. Power for the motor is delivered through wires 6 and 7, the wire 7 extending directly to the motor and wire 6 being connected with a switch arm or blade 8 which is normally in its opened position and moved to a closed position by a relay 9. A wire 6' constituting an extension of wire 6 extends from the switch 8 to the motor, and the wires 6 and 7 are connected with a terminal socket 10 with which a power cable is connected, as shown in Figure 2. A plate 11 is mounted in a wall of a casing 12, and this plate carries the socket 10 and also carries a master switch 13 interposed in the wire 6 and by means of which the device may be rendered operative or inoperative when a feed wire or cable leading from an outlet of a wiring system for a building is plugged into the socket 10. Current is delivered to the mercury switches 2 and 3 by wires 14 and 15 and the mercury switches are connected with the relay 9 by a wire 16 having branches 17 leading to the switches. A wire 18 extends from the relay to the wire 7.

An electrically operated clock 19 is set into an opening formed in a wall of the casing, as shown in Figures 1 and 4, and this clock is connected with the power wires 6 and 7 by wires 20 and 21 so that it will operate when the switch 13 is closed and there has also been provided a pilot light 22 which is connected with the wires 6 and 7 by wires 23 and so mounted in the casing that it will show through the window 24 mounted in the wall of the casing and allow an attendant to readily determine whether the apparatus is in working order. The clock is of conventional construction and has a shaft 24 which projects from its inner or rear wall. There has also been provided an adjusting shaft 25 which projects from the clock and carries a sprocket wheel 26 about which is trained a sprocket chain 27. The chain extends upwardly and is trained about a sprocket wheel 28 carried by a shaft 29 which is rotatably mounted and projects from the casing above the clock and at its outer end carries a knob 30 by means of which it may be turned to adjust the

clock. A shaft 31 is rotatably mounted through panels 32 and 33 located within the casing 12 and this shaft is connected with the shaft 24 of the clock by a shaft 34. Upon the shaft 31 is fixed a small gear 35 meshing with a large gear 36 carried by a shaft 37, the ratio between gears 35 and 36 being such that a shaft 31 rotates eight times to complete one rotation of shaft 37. It will thus be seen that shaft 31 rotates once in twelve hours whereas shaft 37 makes one complete rotation every ninety-six hours. A disk 38 is fixed upon shaft 31 and a disk 39 is fixed upon shaft 37. Adjacent its periphery the disk 38 is formed in its opposite side faces with threaded sockets to receive pegs or pins 40 and 41 for engaging the switches 42 and 43 to which the wires 14 and 15 are attached and holding them closed as long as the pins are in engagement with the switches. The pins 40 are in staggered relation to the pins 41 and the pins of the sets are so spaced from each other circumferentially of the disk 38 that during rotation of the disk the switch 42 will be engaged by a pin 40 every twenty minutes and the pins 41 will engage the switch 43 every twenty minutes. One of the switches will be closed every ten minutes but the switches 42 and 43 will be alternately closed instead of at the same time. By tilting the bar 4 the switches 2 and 3 may be one closed and the other opened and flow of current through the wires 14 and 15 controlled independent of opening and closing of the switches 42 and 43.

The disk 39 carries arcuate strips 44 and 45 which extend circumferentially of the disk and project from opposite side faces thereof, there being two strips 44 and four strips 45. Upon referring to Figures 4 and 5 it will be seen that the strips 44 are diametrically opposite each other and that strips 45 are spaced from each other equal distances about the disk. These strips are provided to engage the long arms of switches 46 and 47 and close the same, the switch 46 being closed twice for each rotation of disk 39 and the switch 47 being closed four times for each rotation of the disk. Another strip 48 is secured upon the marginal edge face of the disk for engaging the long arm of a switch 49 and closing it once for each rotation of the disk. The strips are of such length relative to the circumference of the disk 39 that during a rotation of the disk once in ninety-six hours the strips 44 will close switch 46 once each forty-eight hours and hold it closed for twelve hours each time it is closed, the contacts 45 will engage the switch 47 once each twenty-four hours and hold it closed twelve hours each time, and the strip 48 will engage the switch 49 each ninety-six hours and hold it closed for twelve hours each time. It will thus be seen that each contact holds the companion switch closed for 12 hours but that the time interval between the closing of the switches will vary in accordance with the relation of the switches to the length of the circumference of the disk 39.

It is desired to have the relay 9 energized when selected ones of switches are closed during rotation of the disks 38 and 39 and in order to do so there has been provided a selector switch 50 including a block of insulation 50' carrying terminals 51 and 52 from which extend wires 53 and 54 and other terminals 55, 56 and 57 from which extend wires 58, 59 and 60. The wire 53 and its branches are connected with contacts of the switches 42, 43, 46, 47 and 49 and the wires 58, 59 and 60 and connected with the other contacts of the switches 46, 47, and 49, the wire 54 being cut into the wire 16 between the relay 9 and the mer-

cury switches 2 and 3. The terminal 61 is connected with the power wire 6 and by turning the switch arm 62 the terminal 61 may be selectively connected with the terminal 51, 52, 55, 56, or 57 and a selected one of the switches 42, 43, 46, 47, or 49 will be rendered operative and close a circuit when the master switch 13 is closed. It will thus be seen that while the motor will run for twelve hours when a switch is closed the time intervals between running of the motor may be controlled. The switches 46, 47 and 49 are carried by a lever 63 pivoted upon the shaft 37 and projecting through a slot 64 formed in the top of the casing 12, and referring to Figure 5 it will be seen that by manually moving the lever from the position shown in full lines to that indicated by dotted lines the switches may be shifted a distance corresponding to the distance between ends of the contacts 45 and as this distance represents twelve hours of time the lever may be manually moved from a position in which all of the switches will each be closed during day time to a position for closing the switches at night, and day or night sprinkling may be selectively accomplished. The terminal or blank point 65 is provided upon the block of switch 50 so that by adjusting this switch the pilot light and the clock can operate continuously when the switch 13 is closed. When the switch arm is engaged with terminal 52 which is connected with the wire 16 the relay will be held closed and the motor allowed to run continuously for demonstration purposes.

Having thus described the invention, what is claimed is:

1. In a time controlled switch mechanism, a rotatably mounted shaft adapted to have rotary motion transmitted to it at predetermined speed, a disk carried by said shaft and turning therewith, a lever pivotable upon said shaft and extending radially thereof with its outer end portion projecting beyond the periphery of the disk, a pin projecting from a side of the lever and extending transversely across the peripheral edge face of the disk in spaced relation thereto, switches carried by said pin and each having a stationary contact and a movable contact, certain of said switches being located at opposite sides of the disk and another switch having its movable contact resting upon the peripheral edge face of the disk, and strips mounted against the side faces and the edge face of the disk and extending circumferentially of the disk for engagement with the movable contacts of the switches to individually close the companion switches and hold the said switches closed for a predetermined length of time during rotation of the disk, the strip on the edge face of the disk being longer than the strips at the sides of the disk and the strips at the sides of the disk being spaced from each other circumferentially of the disk, said lever being tiltable about the shaft for movement circumferentially of the disk and thus control the time of day or night at which the strips move into engagement with the movable contacts to close the switches.

2. In a time controlled switch mechanism, a rotatably mounted shaft, a disk carried by said shaft and turning therewith, a lever carried by said shaft and tiltable about the shaft circumferentially of the disk, strips mounted against opposite side faces and upon the peripheral edge face of said disk, said strips extending circumferentially of the disk, there being a single strip upon the edge face of the disk and a plurality of strips upon its side faces spaced from each other cir-

cumferentially of the disk, the strips upon one side face of the disk being spaced from each other a less distance than the strips upon the other side of the disk and are of greater number, and switches carried by said lever and disposed in position for engagement with cooperating strips carried by the disk whereby the switches will be individually and intermittently closed during rotation of the disk, tilting of the lever about the shaft serving to move the switches as a group to adjusted positions circumferentially of the disk.
